Attorneys.

UNITED STATES PATENT OFFICE.

WILLIAM H. ROSE, OF JERSEY CITY, NEW JERSEY.

CONTAINER.

Application filed July 18, 1922. Serial No. 575,799.

To all whom it may concern:

Be it known that I, WILLIAM H. ROSE, a citizen of the United States, and a resident of Jersey City, Hudson County, State of New Jersey, have invented certain new and useful Improvements in Containers, of which the following is a specification.

This invention relates to containers and particularly to a container having walls of paper or other fibrous material and metallic closures for the ends of the same.

The object of the invention is to provide a construction in which the walls of the container may be made heavy and rigid and in which the heads or closures for the same are firmly and permanently attached to the walls of the container. The invention is particularly useful where large containers or barrels are required for the packing or transportation of material since it provides a construction in which the walls may be made thick and heavy so as to be strong and durable and in which the heads are very securely fastened to the walls.

The invention is set forth in detail in the following specification and illustrated in the accompanying drawings in which:

Figure 1 shows the container provided with one form of construction for securing the heads or closures on the same;

Figures 2, 3, 4, 5, 6 and 7 are detached sectional views showing various forms of securing means for holding the heads or closures on the container;

Figure 8 is an edge view of a portion of the closure such as employed in the construction shown in Figure 1;

Figure 9 is an edge view of a portion of the closure such as employed in the modification illustrated in Figure 6.

The body of the container forming the subject matter of the present invention is made up of two portions, an inner cylindrical wall 10 and an outer cylindrical wall 11. These walls, as illustrated in the drawing are made heavy so as to maintain their form during severe usage and to offer substantial resistance to any side thrusts. The tubes or members composing the walls 10

and 11 are preferably formed separately and assembled by inserting one within the other. If desired the outer wall 11 may be formed by wrapping paper material around the inner wall as described in my copending application Ser. No. 575,798. Preferably the tubes 10 and 11 are glued together, the

glue being applied to one or both of the tubes before they are assembled. It is apparent that the tubes may be made of any thickness desired and when assembled and glued together as stated a very strong and rigid construction is produced.

With the body of the container constructed as described, the heads or closures for the container may be secured in position in a very effective manner, and so arranged as to cover and protect the ends of the tubes 10 and 11. To this end the heads or closures 12 are applied to each end of the container, each of these heads being provided with a flange 13 which is arranged between the outer and inner walls of the container and with a flange 12^a which is preferably made of sufficient width to overlie the ends of the outer wall 11. The heads 12 may also be provided with any desired form of opening 12^b to which a cover may be applied.

For securing the flanges 13 of the heads in position between the walls 10 and 11 various means may be employed. In the form of construction illustrated in Figure 1 the flange 13 is provided with outwardly projecting inclined prongs 14 which extend toward the base or inner end of the flange. This particular construction of prongs is also illustrated in Figure 8 of the drawing. It will be apparent that where the flanges 13 of the closures are provided with prongs of this character the flanges may be inserted between the inner and outer walls 10 and 11 after said walls are assembled, and when thus inserted, the prongs 14 will engage and embed themselves more or less in the material of the outer wall 11.

If desired the prongs on the flanges 13 may be arranged to project inwardly and engage the inner wall 10 as illustrated at 15 in Figure 2.

It is, of course, apparent that the prongs on the flanges 13 may be so arranged that one series will project inwardly and the other outwardly as illustrated at 16 and 16^a in Figure 3, the former engaging the outer wall 11 and the latter the inner wall 10.

A somewhat different arrangement for securing the flange in position between the walls is illustrated in Figure 4 in which the flange is provided with a series of inwardly inclined prongs 18 and with a series of openings 17 preferably arranged as illustrated in Figure 9. The prongs 18 will engage and embed themselves in the material

forming the inner wall 10, while the openings 17 will serve as additional securing means by reason of the fact that the glue employed between the inner and outer walls 10 and 11 will enter these openings and thus tend to lock the flange in position between the walls.

In the construction shown in Figure 5, the flange 13 is provided with a series of 10 openings 17 such as illustrated in Figure 9 and in addition thereto a series of outwardly projecting inclined prongs 19 is similar to the prongs 14 of Figure 1.

Figure 6 illustrates a further modified 15 construction in which the flange 13 is provided only with the openings 17. As already pointed out with a construction of this kind the glue will enter the openings 17 and serve to lock the flange 13 in position between the walls 10 and 11. In some cases such openings alone will therefore form sufficient securing means for holding the heads in position on the container.

In Figure 7 there is illustrated a combination of all the various securing means heretofore described, the flange in this form of construction being provided with openings 17 and with outwardly projecting inclined prongs and upwardly projecting inclined prongs 21.

By the construction herein described, it is possible to produce containers which are very strong and capable of resisting any ordinary usage to which they are subjected even when constructed to contain large quantities of material and the various arrangements for securing the heads or closures in position being arranged between the two heavy walls of the container are more or less protected from injury and serve to very securely close the ends of the container.

Having thus described my invention what I claim as new and desire to secure by Letters Patent is:

1. A container having a cylindrical body formed of a heavy inner tube of paper material and a heavy outer tube of paper material surrounding and closely fitting the inner tube, a metallic closure for said container having a flange positioned between said tubes, said flange having a series of outwardly projecting prongs adapted to engage and embed themselves in the inner surface of said outer tube.

2. A container having a cylindrical body formed of a heavy inner tube of paper material and a heavy outer tube of paper material surrounding and closely fitting the inner tube, a metallic closure for said container having a flange positioned between said tubes, said flange having a series of inwardly inclined prongs adapted to engage and embed themselves in the outer surface of the inner tube.

3. A container having a cylindrical body formed of a heavy inner tube of paper material and a heavy outer tube of paper material surrounding and closely fitting the inner tube, a metallic closure for said container having a flange positioned between said tubes, said flange having a series of outwardly inclined prongs and a series of inwardly projecting prongs adapted to engage respectively the inner surface of the outer tube and the outer surface of the inner tube.

4. A container having a heavy cylindrical body of paper material formed of a heavy inner tube of paper material and a heavy outer tube of paper material surrounding and closely fitting the inner tube, a metallic closure for said container having a flange positioned between said tubes, said flange having a series of openings therein for receiving glue, whereby said closure is secured in position on the container.

5. A container having a cylindrical body formed of a heavy inner tube of paper material and a heavy outer tube of paper material surrounding and closely fitting the inner tube, a metallic closure for said container having a flange positioned between said tubes, said flange having a series of outwardly projecting prongs adapted to engage and embed themselves in the inner surface of said outer tube, said flange also having a series of openings therein into which glue may flow and thereby further secure said flange in position.

6. A container having a cylindrical body formed of a heavy inner tube of paper material and a heavy outer tube of paper material surrounding and closely fitting the inner tube, a metallic closure for said container having a flange positioned between said tubes, said flange having a series of inwardly inclined prongs adapted to engage and embed themselves in the outer surface of the inner tube, said flange also having a series of openings therein into which glue may flow and thereby further secure said flange in position.

7. A container having a cylindrical body formed of a heavy inner tube of paper material and a heavy outer tube of paper material surrounding and closely fitting the inner tube, a metallic closure for said container having a flange positioned between said tubes, said flange having a series of outwardly inclined prongs and a series of inwardly projecting prongs adapted to engage respectively the inner surface of the outer tube and the outer surface of the inner tube, said flange also having a series of openings therein into which glue may flow and thereby further secure said flange in position.

8. A cylindrical container having a body composed of a heavy inner tube of paper

material and a heavy outer tube of paper material surrounding and closely fitting said inner tube, a metallic closure for the end of said container having a flange positioned between said tubes, said flange being provided with means by which the same is secured in position between said tubes, said closure also having a flange extending outwardly beyond said first named flange and overlying the end of said outer tube. 10
In testimony whereof I hereunto affix my signature.

WILLIAM H. ROSE.
